Des. 203,580
Patented Feb. 1, 1966

203,580

AUTOMATIC CLOTHES BRUSH OR SIMILAR ARTICLE

William J. Cook, Trumbull, Conn., assignor to General
Electric Company, a corporation of New York

Filed Mar. 1, 1965, Ser. No. 84,006

Term of patent 14 years

(Cl. D9—2)

Fig. 1.

Fig. 2.

Fig. 3.

Fig. 4.

Fig. 5.

Fig. 6.

Fig. 7.

FIG. 1 is a front perspective view of an automatic clothes brush embodying my new design;

FIG. 2 is a right side elevational view thereof;

FIG. 3 is a front elevational view thereof;

FIG. 4 is a rear elevational view thereof;

FIG. 5 is a left side elevational view thereof;

FIG. 6 is a top plan view thereof; and

FIG. 7 is a bottom plan view thereof.

It is to be understood that the surface ornamentation partially omitted in FIG. 3 covers the entire area surrounding the centrally located rectangular shaped portion thereof.

I claim:

The ornamental design for an automatic clothes brush or similar article, substantially as shown and described.
